UNITED STATES PATENT OFFICE.

HUGO H. KRAUS, OF CHICAGO, ILLINOIS.

ARTIFICIAL-TOOTH MOUNTING.

Application filed May 10, 1917. Serial No. 167,766.

To all whom it may concern:

Be it known that I, HUGO H. KRAUS, a citizen of the United States, and a resident of the city of Chicago, county of Cook, and State of Illinois, have invented certain new and useful Improvements in Artificial-Tooth Mountings, of which the following is a specification.

My invention relates to improvements in artificial tooth mountings and has for its object the provision of an improved construction of this character by means of which artificial teeth may be readily and securely mounted.

A further and particular object of my invention is to provide a structure of the class mentioned wherein the artificial teeth are directly connected to the bridge without the interposition of metallic or similar elements.

The invention consists in the combinations and arrangements of parts hereinafter described and claimed.

The invention will be best understood by reference to the accompanying drawings forming a part of this specification, and in which,

Fig. 1 is a top plan view of a tooth mounting embodying my invention,

Fig. 2, a side elevation of the same,

Fig. 3, a view similar to Fig. 2 with the artificial teeth removed,

Fig. 4, a top plan view corresponding with Fig. 3,

Fig. 5, a side view of an artificial tooth employed in the construction illustrated in Figs. 1 to 4,

Fig. 6, an inner face view of said tooth,

Fig. 7, a bottom plan view of a modified form of construction,

Fig. 8, a front view of the same.

Fig. 9, a view similar to Fig. 7, but with the artificial teeth removed,

Fig. 10, a view similar to Fig. 8 with the artificial teeth removed,

Fig. 11, a side view of one of the teeth employed in the construction illustrated in Figs. 7 to 10, and

Fig. 12, an inner face view of the construction illustrated in Fig. 11.

The form of construction illustrated in Figs. 1 to 6 inclusive, comprises a bridge 13 having tooth crowns or caps 14 and 15 located at the ends thereof and adapted to fit over and be adhesively secured to the corresponding teeth in the human jaw, the

construction illustrated being adapted for use in mounting the corresponding teeth in the lower right jaw. Tooth receiving sockets 16 are provided on the top of the bridge 13, are open on their outsides and are provided with securing flanges 17 on their lateral edges. The artificial teeth to be mounted are in the form of shallow bodies 18 and 18' adapted to fit the respective sockets 16, and having their upper or exposed surfaces 19 roughened or indented to imitate the natural surface of the corresponding teeth. Each of the bodies 18 is provided on its sides with grooves 20 adapted to fit over the corresponding flanges 17 and with a depending apron 21 adapted to overhang the outer side of the body 13 to imitate the corresponding portions of the natural teeth.

In use, the crowns 14 and 15 are fitted to the corresponding teeth in the jaw and are secured thereover by suitable cement or other adhesive, the artificial teeth 18 and 18' being secured in the bridge as indicated. By this arrangement, the pressure on the teeth is transmitted directly to the bridge, inasmuch as the bodies of the teeth are mounted on the pressure side of the bridge, that is, the side of the bridge to which the pressure is directly applied in chewing.

The form of construction illustrated in Figs. 7 to 12 inclusive, is adapted for use in replacing the upper incisors or front teeth. In this construction, a bridge 22 is provided with tooth crowns or caps 23 and 24 at its ends adapted to fit over the corresponding incisors just as before. The bridge 24 is provided on its outer face with tooth receiving sockets 25 having upwardly converging securing flanges 26 at their sides. The teeth 27 to be inserted are provided on their rear sides with grooves 28 to fit the flanges 26 and with an abutment 29 fitting against the lower or pressure edge of the bridge 24, so that the chewing pressure is transmitted directly to said bridge. The mounting is secured in place substantially as above outlined.

While I have illustrated and described the preferred forms of construction for carrying my invention into effect, these are capable of variation and modification without departing from the spirit of the invention. I, therefore, do not wish to be limited to the precise details of construction set forth, but

desire to avail myself of such variations and modifications as come within the scope of the appended claims.

Having described my invention what I claim as new and desire to secure by Letters Patent is:

1. An artificial tooth mounting comprising a bridge, socket in the face of the bridge, securing flanges on the sides of said socket intermediate the bottom and outer edges thereof, a tooth slidably fitting said socket and provided with grooves fitting said flanges and abutment on said tooth contacting with the bridge, the abutting faces

thereof being in the path of the greatest pressure and at substantially right angles thereto, substantially as described.

2. A device as set forth in claim 1 in which the securing flanges are substantially parallel to the bottom of the socket, substantially as described.

In testimony whereof I have signed my name to this specification in the presence of two subscribing witnesses.

HUGO H. KRAUS.
